UNITED STATES PATENT OFFICE.

JOHN C. BROOKS, OF PATERSON, NEW JERSEY.

LOOM.

1,368,691.

Specification of Letters Patent. Patented Feb. 15, 1921.

Application filed May 13, 1920. Serial No. 381,190.

To all whom it may concern:

Be it known that I, JOHN C. BROOKS, a citizen of the United States, residing at Paterson, county of Passaic, State of New Jersey, have invented an Improvement in Looms, of which the following description, in connection with the accompanying drawing, is a specification, like characters on the drawing representing like parts.

10 This invention relates to looms of that type which are constructed to deliver the picks of filling to the shed by means of an air blast which acts directly on the filling, and the object of the invention is to provide a loom of this type having improved means for controlling the filling so that the latter may be accurately and properly laid in the shed.

20 My improved loom is provided with a nozzle through which the weft or filling is delivered to the shed and novel means for pulling off a length of filling from the source of supply at each pick and then releasing said length and afterward delivering said pulled-off length to the shed by a blast of air. My invention also comprises an improved means for cutting each length of filling close to the edge of the fabric after it has been introduced.

30 In order to give an understanding of my invention, I have illustrated in the drawings a selected embodiment thereof which will now be described, after which the novel features will be pointed out in the appended 35 claims.

In the drawings, Figure 1 is a front view of a loom embodying my invention;

Fig. 2 is a side view thereof with the filling pulling-off feature omitted;

40 Fig. 3 is a section on the broken line 3—3, Fig. 1;

Fig. 4 is a side view of the filling-engaging fingers of the pulling-off mechanism showing said fingers in operative position;

45 Fig. 5 is a view showing the fingers released;

Fig. 6 is a view showing the filling-cutting element;

Fig. 7 is a detail showing the air-controlling valve.

In the loom herein illustrated, 1 indicates the loom frame which may be of any suitable or usual construction; 2 the lay having the reed 3 thereon; 4 the reed cap or hand rail; 5 the lay-swords on which the lay is mounted and which are supported by the

usual rock-shafts 6; 7 the harnesses and 8 the cams mounted on the cam shaft 9 which actuate the harnesses through the harness-levers 10.

60 The parts thus far described are or may be all as usual in looms and form no part of my present invention.

In my improved loom, the weft or filling is delivered to the shed through a nozzle 11 by means of an air blast. I may arrange the loom so that the weft will all be delivered from one side thereof or I may employ two nozzles, one on each side, so that the filling will be delivered alternately from 70 opposite sides. I have herein illustrated two nozzles 11 which are supported by the lay on opposite sides thereof. Each nozzle is branched, one branch 12 being connected to a source of air supply, not shown, by a 75 flexible pipe 71, and the other branch 13 receiving the filling 14 from the source of supply. These two branches come together at 15, and the delivery end 16 of the nozzle is directed longitudinally of the lay and is 80 situated in front of the reed 3. When, therefore, an air blast is delivered into the branch 12 of the nozzle, this will tend to draw the filling 14 through the branch 13 and blow the latter across the shed.

85 I have provided herein novel means whereby during each forward beat of the lay a length of filling will be drawn off from the source of supply which length will be released just before the lay reaches the 90 back limit of its movement, at which time a blast of air is delivered through the nozzle to blow the pulled-off length of filling across the shed.

95 I have herein shown a filling pull-off device for each nozzle, said pull-off devices being situated on opposite sides of the loom. Each pull-off device is supported in a suitable frame 17 at the side of the loom and comprises an endless chain element 18 passing around sprockets 19 and 20 carried by said frame and having thereon pulling-off fingers 21 adapted to engage the filling 14 and draw off a length from the source of supply and then to release the length when 100 a sufficient amount has been pulled off. The filling is shown as coming from a source of supply 22 and as extending through suitable guide-eyes 23, 24, 25, 26 on its way to the nozzle. The guide-eyes 24 and 25 are situated on opposite sides of the path of movement of the pulling-off finger 21 so that as

said finger is moved downwardly by the chain, it will engage the filling between the guide-eyes 24, 25 and draw off a length of filling from the source of supply, forming 5 said length into a bight or loop 27. When the proper length for the width of the cloth has been withdrawn, the fingers release this bight or loop.

The pulling-off finger 21 is a duplex affair and is carried by a support 28 that is pivotally connected to one of the links of the chain at 29. The fingers 21 are situated at the lower end of the support 28 and at its upper end said support has two laterally-extending fingers 30 that are adapted to engage two tracks 31, 32. The tracks 31, 32 extend above the guide-eyes 24, 25, and as each support 28 is carried over the upper sprocket 19 and begins to move downwardly, the projections 30 on said support engage the upper curved end 33 of the track thereby swinging the support into vertical position with the fingers 21 extending horizontally, as shown in Fig. 4. The fingers 25 are thus brought into filling-engaging position before they reach the filling extending between the guide-eyes 24, 25, and, consequently, as the support with the fingers 21 is moved downwardly, the fingers engage 30 the filling and draw off a length from the source of supply. When the support 28 has reached the position where the projections 30 pass off from the lower end of the tracks 31, 32, there is nothing to hold said support 35 in its vertical position, and the tension of the filling acting on the fingers 21 will swing said support into the position shown in Fig. 5 thereby releasing the fingers from the filling. The sprocket chain 18 should be 40 driven at the proper speed and in proper timed relation with the movements of the loom so that a correct length of filling will be drawn off by one or the other filling pull-off mechanisms at each beat of the lay. 45 Where there are two filling pull-off devices and two nozzles, then the pull-off device on each side of the lay will be arranged to pull off its length of filling at every other pick so that the picks will be pulled off alternately on opposite sides of the lay. Each 50 chain 18 may have one or more of these pull-off fingers mounted thereon, depending on the operations of the loom. The sprocket chains 18 may be driven in any suitable 55 way. I have herein illustrated the lower sprocket wheel 20 of each pulling-off device as driven from the cam shaft 9 by means of suitably-timed sprocket-chain gearing 34.

In order that the pulling-off device may 60 operate properly I have provided herein means to clamp the filling between the nozzle and the guide-eye 25 while the finger 21 is acting on the filling thereby to insure that the filling will be drawn off from the source 65 of supply rather than being pulled back

from the nozzle, and have also provided another clamping device to act on the filling between the source of supply and the guide-eye 24 after the filling has been released and while the air blast is operating to blow 70 the filling through the shed. The first-named clamping device is herein shown as a clamping member 35 arranged to clamp the filling against the front face of the hand-rail 4 adjacent the end of the nozzle 75 branch 13. There is a clamping member 35 at each end of the lay, and each member is carried by a swinging lever 36 pivoted to the lay at 37 and acted upon by a coiled spring 38 which tends to move it into operative position in engagement with the hand-rail. Means are provided for releasing the clamping member 35 at such times as the filling is to be blown across the lay and where the filling is introduced from 85 both sides of the lay, as herein illustrated, each clamping member will be released at every other pick.

For releasing each clamping member 35, I have shown a releasing lever 39 for each 90 clamping member, each releasing lever being pivoted to the loom frame at 40 and being connected to the harness mechanism so that it will be raised and lowered therewith. When each lever 39 is in its lowered 95 position, the outer end thereof is in the path of movement of the upper end of the lever 36 so that upon the backward movement of the lay, the lever 36 engages the releasing lever 39 and thereby causes the clamping 100 lever to swing away from the lay and thereby release the filling. So long as the releasing lever 39 is in its elevated position, the corresponding clamping lever 36 will be in its operative clamping position. The two 105 releasing levers 39 are connected to different harnesses so that they operate alternately, and upon one backward movement of the lay one of the levers will release its clamping lever 36, and upon the next backward 110 movement of the lay, the other releasing lever will release its clamping lever. The clamping levers 36 are thereby alternately actuated. Each releasing lever 39 is shown as connected to a harness by a flexible connection 41, but any other way of operating the levers 39 might be employed without departing from the invention. The other clamp which is situated between the pulling-off fingers and the source of supply 115 is herein shown in the form of a fixed block or plate 42 over which the filling passes, and a movable clamping member 43 adapted to move toward and from the block 42 and thereby clamp and unclamp the filling. It 120 is necessary, of course, that the clamping member 43 should be inoperative while the fingers 21 are pulling off a length of filling, so that the filling may be freely drawn off from the source of supply. I 125 130

have, therefore, provided herein means which are actuated by the fingers 21 for rendering the clamp 43 inoperative. The track 32 is shown as carried on arms 44 which are pivoted to the framing 17 at 45, and said arms are connected by a yoke 46 to which the clamp 43 is secured by means of arms 47. Each arm is acted on by a spring 48 and these springs normally tend to maintain the 10 clamping member 43 in its operative position. Whenever the supporting member 28 is brought into a position by the sprocket chain so that one of the projections 30 engages the track 32, the pressure of said 15 projection against the track will rock it about the pivots 45 thereby separating the clamping member 43 from the block 42 and unclamping the filling. The filling will remain unclamped so long as the support 28 20 is passing over the track 32 and while the filling is being pulled off from the source of supply. When the finger 30 passes out of engagement with the lower end of the track 32, then the springs 48 return the clamping 25 member 43 to its clamping position and hold the filling clamped until the projections 30 on another support 28 comes into engagement with the track 32 again.

The clamping member 35 is arranged so 30 that it operates alternately with the clamping member 43.

Any suitable means may be provided for delivering the air blast to the nozzle after the length of filling has been pulled off 35 from the source of supply and when the lay is at the back end of its stroke. Where the nozzle is connected to a permanent source of air supply, such, for instance, as a tank containing compressed air, I may provide a 40 valve mechanism in said pipe 71 which is normally closed, but which will be automatically opened when the lay beats back. In Fig. 7 I have shown such a valve which comprises a cylinder 72 interposed in the pipe 45 71 and having ports with which the two sections of said pipe communicate, and a piston or plunger 73 which normally closes said ports. This plunger 73 is provided with a stem 74 having a collar 75 thereon, and a 50 spring 76 surrounds the stem and acts on the collar and normally holds the plunger in the position shown in Fig. 7. The valve with its stem moves back and forth with the lay, and the loom frame is provided with a 55 projection 77 situated to be engaged by the stem 74 just before the lay completes its backward movement, so that while the lay is passing its rear center, the plunger will be acted on by the projection 77 thereby shifting 60 the piston valve 73 into a position to open the ports. As soon as the ports are open a blast of air will be delivered through the nozzle to blow the pulled-off length of filling through the shed. The construction 65 will preferably be such that the valve will

be open for an instant only as a momentary puff or blast of air is sufficient to perform the function of delivering the filling across the shed.

I have also provided herein novel means 70 for cutting each filling after it has been delivered across the shed. The lay is provided with two spaced uprights 49 at each end thereof and adjacent the delivery end of the nozzle, said uprights being situated 75 in front of the nozzle so that the filling will be blown between the uprights and the reed. Pivoted to the rear of the lay at each end is a knife 50, each knife being carried by a stem 51 which is pivoted to the lay at 52. 80 Each knife 50 normally stands at the rear of the reed and means are provided for swinging the knife forwardly into the dotted line position thereby to engage and sever the filling thread when the lay beats up. For 85 this purpose, the lay is provided with a plunger 53 slidably mounted through the lay and engaging at one end the lower end of the stem 51 below the pivot 52 and the other end projecting forwardly beyond the 90 lay and provided with a head 54. A return spring 55 is confined between the lay and the head 54. The plunger 53 is so situated that when the lay beats up the head thereof 95 will engage the breast-beam or some other fixed part of the loom and will be forced to the rear against the action of the spring 55 thereby swinging the knife forwardly and causing it to sever the filling thread.

It will be noted that I have shown two 100 fingers 21 carried by each support 28. The object of having two fingers is to provide for forming two bights in each filling thread as it is drawn off. This could be done by placing a second stationary guide between 105 the fingers so that each finger would pull off a separate bight. In this way twice the length of filling will be pulled off at each actuation of the fingers than where one bight 110 only of filling is drawn off.

While I have illustrated in the drawings a selected embodiment of my invention, I do not wish to be limited to the constructional details shown.

I claim:

1. In a loom, the combination with means to form sheds in the warp threads, of means to draw off a length of filling thread from a source of supply and then release said length from the drawing-off means, means 120 to lay said length in a shed by an air blast, and means to engage the filling thread while said length is being pulled off to prevent it from being pulled out from the shed.

2. In a loom, the combination with means to form sheds in the warp, of a filling-delivery nozzle, to which the filling is led from its source of supply, means for drawing off a length of filling from the source of supply, means for delivering an air blast to said 130

- nozzle for blowing said filling across the shed, and means to grip the filling adjacent the nozzle while the length is being pulled off thereby to prevent the filling from being withdrawn from the shed.
3. In a loom, the combination with a lay, of means to form sheds in the warp, a filling-delivery nozzle carried by the lay, means for drawing of a length of filling from a source 10 of supply and then releasing said length from the drawing-off means, means to cause an air blast to be delivered through said nozzle when the lay is in its backward position thereby to blow said length of filling across the shed, and means to grip the filling adjacent the nozzle while said length is being pulled off thereby to prevent the filling from being withdrawn from the shed.
4. In a loom, the combination with a lay, 20 of means to form sheds in the warp, a filling-delivery nozzle carried by the lay, means for drawing off a length of filling from a source of supply and then releasing said length, means to cause an air blast to be delivered 25 through said nozzle when the lay is in its backward position thereby to blow said length of filling across the shed, and means to grip the filling adjacent the nozzle while said length is being pulled off thereby to prevent the filling 30 from the shed and to release the filling while the air blast is operative.
5. In a loom, the combination with a lay, of means to form sheds in the warp, a filling-delivery nozzle carried by the lay, means for drawing off a length of filling from a source of supply and then releasing said length, means to cause an air blast to be delivered through said nozzle when the lay 35 is in its backward position thereby to blow said length of filling across the shed, means to clamp the thread adjacent the nozzle, and means to release said clamp when the lay moves backwardly.
- 40 6. In a loom, the combination with a lay, of a filling-delivery nozzle carried thereby, a filling pull-off device for pulling off a length of filling from a source of supply and then releasing said length, two filling clamping devices, one situated to act on the filling between the pulling-off device and the nozzle and the other between said pulling-off device and the source of supply, and means to cause said clamping devices to operate 45 alternately.
7. In a loom, the combination with a lay, of a filling-delivery nozzle carried thereby, a filling pull-off device for pulling off a length of filling from a source of supply and then releasing said length, two automatically-operative filling clamping devices, one situated to act on the filling between the pulling-off device and the nozzle and the other between said pulling-off device and the source of supply, and means to render 55 the last-named clamping device inoperative while said length of filling is being pulled off and the first-named clamping device inoperative while said length is being blown through the shed.
8. In a loom, the combination with a lay, of a filling-delivery nozzle carried thereby, a filling pull-off device for pulling off a length of filling from a source of supply and then releasing said length, two automatically-operative filling clamping devices, one situated to act on the filling between the pulling-off device and the nozzle and the other between said pulling-off device and the source of supply, means actuated by the pulling-off device to render the last-named clamping device inoperative while said length of filling is being pulled off, and means to render the first-named clamping device inoperative while said length is being blown through the shed.
9. In a loom, the combination with a lay, of a filling-delivery nozzle carried thereby, a filling pull-off device for pulling off a length of filling from a source of supply and then releasing said length, two automatically-operative filling clamping devices, one situated to act on the filling between the pulling-off device and the nozzle and the other between said pulling-off device and the source of supply, means actuated by the pulling-off device to render the last-named clamping device inoperative while said length of filling is being pulled off, and means to render the first-named clamping device inoperative while said length is being blown through the shed.
10. In a loom, the combination with a lay, of a filling-delivery nozzle, means to deliver an air blast therethrough for blowing the filling across the shed, and means for drawing off a length of filling for each pick and then releasing said length, said means comprising an endless chain element and a pulling-off finger carried thereby.
11. In a loom, the combination with a lay, of a filling-delivery nozzle, means to deliver an air blast therethrough to blow filling across the shed, an endless-chain element, a pulling-off finger pivotally carried thereby, means to cause the finger during the movement of the chain to engage the filling thereby to draw off a length from the source of supply and then to release the filling.
12. In a loom, the combination with means to form sheds in the warp threads, of a filling-delivery nozzle to which filling is led from a source of supply, a constantly-moving device adapted to engage said thread between the nozzle and the source of supply and draw off a length of filling from said source of supply and then free said length from said device, means to grip the filling.

adjacent the nozzle while said length is being pulled off thereby to prevent the filling from being withdrawn from the shed; and means for delivering an air blast to said nozzle to blow the drawn off length of filling through the shed.

13. In a loom, the combination with means to form sheds in the warp threads, of a filling-delivery nozzle to which filling is led from a source of supply, an endless-chain device, means carried thereby for drawing off a length of filling from the source of supply and then freeing said length from the drawing-off means, and means for delivering an air blast to said nozzle for blowing the freed length of filling through the warp shed.

14. In a loom, the combination with means to form sheds in the warp threads, of a filling-delivery nozzle to which filling is led from a source of supply, an endless-chain device, means carried thereby for drawing off a length of filling from the source of supply and then freeing said length from the drawing-off means, means for delivering an air blast to said nozzle for blowing the freed length of filling through the warp shed, and means to grip the filling adjacent the nozzle while said length is being pulled off to prevent the filling from being withdrawn from the shed.

15. In a loom, the combination with means

to form sheds in the warp threads, of a filling-delivery nozzle to which filling is led from a source of supply, and an endless-chain device, means carried thereby for drawing off a length of filling from the source of supply and then freeing said length from the drawing-off means, means for delivering an air blast to said nozzle for blowing the freed length of filling through the warp shed, and means to grip the filling between the pulling-off device and the source of supply while the air blast is operative thereby to prevent the latter from withdrawing any filling from the source of supply.

16. In a loom, the combination with means to form sheds in the warp threads, of a filling-delivery nozzle to which filling is led from a source of supply, an endless-chain device, means to actuate the latter, a pulling-off finger carried thereby and adapted to engage the filling between the source of supply and the nozzle thereby to draw off a length of filling from the source of supply, means to disengage said filling from the finger when the desired length is pulled off, and means to deliver an air blast through the nozzle to blow said pulled-off length through the shed.

In testimony whereof, I have signed my name to this specification.

JOHN C. BROOKS.
